UNITED STATES PATENT OFFICE.

ALVIN SCHWARTZ, OF NEW YORK, N. Y.

KNITTING-MACHINE.

1,228,483.

Specification of Letters Patent. Patented June 5, 1917.

Application filed June 22, 1916. Serial No. 105,115.

To all whom it may concern:

Be it known that I, ALVIN SCHWARTZ, a citizen of the United States, and residing in the borough of Manhattan of the city of New York, county of New York, in the State of New York, have invented certain new and useful Improvements in Knitting-Machines, of which the following is a specification, reference being had to the accompanying drawings, forming a part hereof.

This invention relates primarily to straight knitting machines of the Lamb type, which have two straight rows of successively operated, independent needles, at opposite sides of the line of travel of the yarn-carrier, and supported on needle-beds inclined upwardly toward the middle line. The main object of the invention is to provide improved means whereby, on machines of this type, it shall be possible to knit flat work with longitudinal, that is, vertical stripes, or with a checked pattern, or with bias stripes, or with zigzag stripes. In its main features the machine to which the invention is applied may be constructed substantially as usual, particularly with respect to the needle-beds, needles, needle-cams, the cam-carrier or carriage, and the means for actuating it, either by hand or power. The invention is particularly concerned with the yarn-guides and the means for controlling the operation thereof. The invention will be more fully explained hereinafter with reference to the accompanying drawings in which it is illustrated and in which,

Figure 1 is a top view of a knitting machine equipped with the improved devices.

Fig. 2 is a view of the same in side elevation.

Fig. 3 is a fragmentary, detail view, on a larger scale, illustrating particularly the yarn-guides and means for actuating and controlling the same.

Fig. 4 is a view in section on the plane indicated by the line 4—4 of Fig. 2.

Fig. 5 is a detail view in section on the plane indicated by the line 5—5 of Fig. 2.

Fig. 6 is a detail view showing a portion of the devices for controlling the movement of the yarn-carriers.

Figs. 7 and 8 are detail views to enlarged scale.

The frame *a* of the machine supports the usual grooved needle-beds *b*, on which are

mounted the usual needles *c*, operated in the usual manner by cams, not shown, which are reciprocated over the needles by the cam-carrier *c'*. The latter is suitably guided and may be reciprocated by any suitable means, as through the link *c*² from the hand-crank *c*³. All of these parts may be constructed and arranged to operate in any usual or suitable manner.

It will be understood that for convenience in illustration the needle-beds are shown to be short and the number of needles on each side to be small, and that in practice the needle-beds may be much longer and the number of needles much greater. The yarn-guides and their controlling devices, also for convenience in illustration, are shown as few in number and as adapted to produce only a fabric with two vertical stripes or with checks in two colors, or with zigzag stripes in two colors, the number of yarn-guides being increased with the length of the needle-beds and according to the results to be produced.

In the embodiment of the invention shown there are two yarn guides *d'* and *d*⁴ at one side of the machine and two yarn-guides *d*² and *d*³ at the other side of the machine. For knitting a fabric with two vertical stripes, the two yarn-guides *d'* and *d*² are used; for knitting a checked fabric in two colors, and for knitting a fabric with bias stripes running in one direction only the three yarn-guides *d'*, *d*² and *d*³ may be used; and for knitting a fabric with zigzag stripes, inclined in both directions, the four yarn-guides *d'*, *d*², *d*³ and *d*⁴ may be used.

The yarn-guides, at opposite sides of the machine are mounted frictionally on rods *d* which are supported at their ends by suitable brackets *d*⁵ from the frame of the machine. The yarn-guides are movable longitudinally on the rods *d*, but with sufficient friction to prevent accidental movement thereof. They are moved by the cam-carrier *c'* through drivers *d*⁶. The engagement between the yarn-guides and the drivers is of a yielding nature, such that the driver may pass beyond the yarn-guide in the continued movement of the cam-carrier, when the yarn-guide is restrained from further movement. To accomplish this result, in the construction shown, the driver *d*⁶ is a plunger with a rounded end seated upon a spring *d*⁷, and the yarn-guide *d'* has a rounded heel *d*⁸ for en-

gagement therewith, so that when the yarn-guide is prevented from further movement the driver will slip over the heel of the yarn-guide and continue its own movement with the cam-carrier.

5 Stops are provided to limit the movement of each yarn-guide, in each direction, at such point as may be required by the pattern of the fabric to be produced, the stops being movable to vary the position according to the pattern. In the construction shown, two rods e' and e^2 are supported parallel with the rods d and respectively in close proximity to the corresponding rod d . They are 10 movable together in longitudinal direction, being conveniently connected at their ends, for this purpose, by cross-bars e , and each is preferably angular in cross-section and is rotatable on its own axis for a purpose to be 15 described, being provided at one end or the other, or at each end, with a handle e^3 . The rods e' , e^2 may be guided for longitudinal movement in the brackets d^5 and may be 20 rotatably supported therein by rotatable bearing blocks d^6 grooved circumferentially and held in position by screws d^{10} , as clearly 25 shown in Fig. 6. The rods e' , e^2 may receive endwise movement through a cross-head f in which they have bearings f' which permit 30 rotation but prevent relative longitudinal movement of the rods and the cross-head, and the cross-head may be split, as at f^2 , and provided with clamping screws f^3 to bind the bearings f' and prevent rotation 35 thereof. The cross-head may have a depending, vertically slotted yoke f^4 for engagement with a pin f^5 in the upper end of a lever f^6 , which is pivoted at f^7 and carries at its lower end a detent pin f^8 for engagement 40 with a fixed segment f^9 . By these means the rods e' , e^2 may be moved longitudinally to any desired extent, within limits, and held in their adjusted position.

The rod e' carries several stops g , g' , g^2 , g^3 45 and the rod e^2 carries corresponding stops h , h' , h^2 , h^3 . Each stop is preferably slipped on the corresponding rod and secured by a set screw, as shown, so that its position on the rod may be adjusted. Each stop is also 50 beveled on its side adjacent the corresponding rod d , for coöperation with a beveled shoulder d^{11} of each thread-guide, as hereinafter described.

It being understood that the machine 55 shown in the drawings is adapted for two-color work and for the formation of a fabric with two vertical stripes or with two rows of checks, or with stripes of two colors, either bias or zigzag, and that the number 60 and arrangement of thread-guides and stops might be varied to produce different patterns, the operation of the machine, so far as the present improvements are concerned will now be described. With the parts in 65 the positions shown in Figs. 1, 2 and 3, it is

assumed that the crank c^3 is rotated contrary clockwise and that the crank having just passed the horizontal position and moving downward, the cam-carrier c' is moved slightly toward the right from its extreme 70 left hand position. The driver d^8 on the rear side of the carrier then stands just behind the heel d^8 of the yarn-guide d' and in the continued movement of the carrier pushes the yarn-guide ahead of it until the 75 yarn-guide strikes the stop g^2 . The yarn-guide d' then ceases its movement, the driver d^8 slipping over the heel d^8 in the continued movement of the cam-carrier. With the parts in the positions shown, the yarn-guide 80 d^2 rests against the right hand side of the stop h^2 during the described movement of the yarn-guide d' . It will be observed, however, that the stops g^2 and h^2 are not in line, the stop h^2 being farther to the left than 85 the stop g^2 . Therefore, just before the yarn-guide d' makes contact with the stop g^2 , the driver d^8 , on the forward side of the cam-carrier engages the yarn-guide d^2 and begins its movement to the right before the 90 yarn-guide d' stops. This arrangement is made in order that the yarn-guide d^2 , which may be supposed to carry a black thread, may lay its yarn into the same needles, then advanced by the cams, into which the yarn 95 carried by the guide d' , which may be supposed to be a red yarn, is laid by the yarn-guide d' , the two stripes being thus united. As the yarn-guide d' stops at the point described, during the right hand movement of 100 the cam-carrier, and the yarn-guide d^2 is carried to the right from that line by its driver, the knitting will be continued with the black yarn. When the yarn-guide d^2 reaches the stop h^3 , its movement will cease 105 and its driver will slip beyond it, in the continued movement of the cam-carrier to the right. The yarn-guide d^4 is shown in a position to be overlapped by the movement of the yarn-guide d^2 , but in the knitting of 110 plain striped fabrics the yarn-guide d^4 would be moved by hand farther to the right before the knitting commences and would be idle. As the cam-carrier moves to the left, from its extreme right hand position, the 115 driver d^8 at the front of the machine will first engage the yarn-guide d^2 and move it from the left hand side of the stop h^3 to the right hand side of the stop h^2 , leaving it there, and the driver d^8 at the rear of the 120 machine will at the same time pick up the yarn-guide d' previously left at the left hand side of the stop g^2 and will move it to the left until its movement is checked by the stop g' , when the driver will slip beyond the 125 yarn-guide d' in the last part of the left hand movement of the cam-carrier and will pick it up again in the first part of the right hand movement of the cam-carrier. These operations will be repeated as long as the forma- 130

tion of the knitted fabric is continued, making a fabric with a red stripe at the left and a black stripe at the right.

If a checked fabric is to be made, both 5 yarn-guides d^2 and d^3 are provided with yarn of the same color, as black, and are brought into operation alternately, while the yarn-guide d' operates alone with yarn of another color, as red. The formation of 10 the first two checks side by side is carried on in the same way as before described with respect to the formation of the two stripes, but when the first two checks have been formed the rods e' , e^2 are moved to the right by a space equal to the width of the check. This carries the yarn-guide d' to the right so that the red yarn carried by it will form the red check at the right. It also carries the yarn-guide d^2 far enough to the right to 15 become idle and carries the yarn-guide d^3 far enough to the right to permit the black yarn carried by it to form the black check at the left hand of the fabric. When the two checks have been completed in the usual 20 manner, the rods e' , e^2 are moved again to the left, to their original position, and the formation of the next two checks with the 25 yarn-guides d' and d^2 is carried on as before.

It is necessary at times in the operation 30 of the machine, as for example, when the yarn-guide d^2 is to be moved to an idle position, that it shall be carried beyond the stop which would otherwise check its movement. It is in order to permit this that 35 the rods e' and e^2 are made rotatable, so that the beveled toe of each stop may be moved out of the path of the point of the beveled shoulder d^{11} of the yarn-guide involved, the rod being returned to its 40 operative position as soon as the yarn-guide has passed the stop involved. The purpose in beveling the toe of each stop and the engaging portion of each yarn-guide is to permit each yarn-guide which has been moved 45 in one direction beyond a stop, through the turning of the rod, to be moved past the stop in the opposite direction, when required, without necessitating the rotation of the rod. There is sufficient flexibility in 50 the rods d , e' and e^2 to permit such a stop and yarn-guide to be separated by the coacting beveled surfaces sufficiently to permit the passage of the yarn-guide beyond the stop in the corresponding direction, while 55 such passage of the yarn-guide beyond the stop in the opposite direction is not possible because of the engagement of the straight sides.

For the formation of bias stripes (of course, with stepped edges) the operation of 60 the machine is carried on as already described with respect to the formation of checks, but with the shifting of the rods e' and e^2 and of the stops at more frequent 65 intervals, the locking segment f' being pro-

vided for this purpose with holes intermediate between the extremes. If these bias stripes run only in one direction, the work can be accomplished with the use of three 70 yarn-guides as already described, but if the stripes are to be zigzag, inclined first in one direction and then in the other, the yarn-guide d^4 , also carrying red yarn, is brought into operation.

It will be understood that in the operation 75 of the improved machine shown in the drawings for the purposes stated, the yarn-guides on opposite sides of the machine are operated in alternation and that, in order that the portion of the fabric of different 80 color may be united, instead of forming separate strips, each yarn-guide on one side must overlap, in its movement, the next yarn-guide on the other side in order that the yarns carried by both yarn-guides may 85 be laid into a common needle. It is therefore necessary that the yarn-guides on opposite sides be offset in different longitudinal planes, as well as that the stops for co-operation therewith be offset in different 90 transverse planes.

It will also be understood that many different patterns can be produced with the improved mechanism, that the number of 95 yarn-guides and stops may be increased according to the requirements of the pattern, and that various changes in details of construction and arrangement may be made to suit the construction of the machine to which the improved device may be applied 100 and the character of the work to be done.

It will be seen further that for some purposes the means for the operation of the 105 yarn-guides in succession might be employed in connection with only one set of needles, the needles of the other set, in the machine illustrated in the drawings, being out of operation, or that alternate yarn-guides might be put out of operation. The 110 special purposes with a view to which the invention was developed find their fullest expression, however, in a machine of the character illustrated.

I claim as my invention:

1. In a knitting machine for knitting vertically striped fabric, the combination with a needle-bed, a set of independent needles and a cam-carrier for actuating the needles successively, of a plurality of yarn-guides free to pass one another, and means to actuate the yarn-guides in succession, each yarn-guide coming to rest after it has moved beyond the initial position of the next succeeding yarn-guide, the movement of which then commences.

2. In a knitting machine for knitting vertically striped fabric, the combination with a needle-bed, independent needles and a cam-carrier for actuating the needles successively, of a plurality of yarn-guides free to pass one 130

- another, and means to actuate the yarn-guides in succession and to carry each beyond the initial position of the next one, each yarn-guide coming to rest after it has moved beyond the initial position of the next succeeding yarn-guide, the movement of which then commences.
3. In a knitting machine for knitting vertically striped fabric, the combination with 10 a needle-bed, independent needles and a cam-carrier for actuating the needles successively, of a plurality of yarn-guides free to pass one another, yielding means carried with the cam-carrier to actuate the yarn-guides in succession, and stops to check the 15 yarn-guides, each yarn-guide coming to rest after it has moved beyond the initial position of the next succeeding yarn-guide, the movement of which then commences.
- 20 4. In a knitting machine for knitting vertically striped fabric, the combination with a needle-bed, independent needles and a cam-carrier for actuating the needles successively, of a rod parallel with the needle-bed, 25 yarn-guides mounted movably on the rod, a yielding driver carried by the cam-carrier to engage the corresponding yarn-guides yieldingly, and means to disengage the yarn-guides from the driver and check 30 their movement at different points, each yarn-guide coming to rest after it has moved beyond the initial position of the next succeeding yarn-guide, the movement of which then commences.
- 35 5. In a knitting machine for knitting vertically striped fabric having two opposed needle-beds and sets of independent needles, and a cam-carrier for actuating the needles of both sets successively, the combination of 40 a plurality of yarn-guides free to pass one another, and means to actuate the yarn-guides in succession, each yarn-guide coming to rest after it has moved beyond the initial position of the next succeeding yarn-guide, the movement of which then commences.
- 45 6. In a knitting machine for knitting vertically striped fabric having two opposed needle-beds and sets of independent needles, 50 and a cam-carrier for actuating the needles of both sets successively, the combination of a plurality of yarn-guides free to pass one another, and means to actuate the yarn-guides in succession and to carry each beyond the initial position of the next one of the opposite set, each yarn-guide coming to rest after it has moved beyond the initial position of the next succeeding yarn-guide, the movement of which then commences.
- 55 7. In a knitting machine for knitting vertically striped fabric having two opposed needle-beds and sets of independent needles, and a cam-carrier for actuating the needles of both sets successively, the combination of 60 a plurality of yarn-guides arranged in al-
- ternation on opposite sides of the longitudinal plane and free to pass one another, and means to actuate the yarn-guides in succession, each yarn-guide coming to rest after it has moved beyond the initial position of the next succeeding yarn-guide, the movement of which then commences.
8. In a knitting machine for knitting vertically striped fabric having two opposed needle-beds and sets of independent needles 75 and a cam-carrier for actuating the needles of both sets successively, the combination of a plurality of yarn-guides arranged in alternation on opposite sides of the longitudinal plane and free to pass one another, 80 and means to actuate the yarn-guides in succession and to carry each beyond the initial position of the next one on the opposite side.
9. In a knitting machine for knitting vertically striped fabric having two opposed needle-beds and sets of independent needles 85 and a cam-carrier for actuating the needles of both sets successively, the combination of a plurality of yarn-guides arranged in alternation on opposite sides of the longitudinal plane and free to pass one another, 90 yielding means carried with the cam-carrier to actuate the yarn-guides in succession, and stops to check the yarn-guides, the stops on opposite sides being offset in transverse planes to permit each yarn-guide to overlap the next in its movement.
10. In a knitting machine for knitting vertically striped fabric having two opposed needle-beds and sets of independent needles and a cam-carrier for actuating the needles of both sets successively, the combination of a plurality of yarn-guides arranged in alternation on opposite sides of the longitudinal plane and free to pass one another, yielding means carried with the cam-carrier to actuate the yarn-guides in succession, stops to check the yarn-guides, the stops on opposite sides being offset in transverse planes 100 to permit each yarn-guide to overlap the next in its movement, and means to shift the positions of the stops.
11. In a knitting machine for knitting vertically striped fabric having two opposed needle beds and sets of independent needles and a cam-carrier for actuating the needles of both sets successively, the combination of rods on opposite sides of the longitudinal mid-plane, yarn-guides mounted 115 movably on said rods, a driver carried by the cam-carrier on each side of the longitudinal mid-plane to engage the corresponding yarn-guides, and means to disengage the yarn-guides automatically from the drivers 120 and check their movement at different points in alternation on opposite sides of the longitudinal mid-plane.
12. In a knitting machine for knitting vertically striped fabric having two opposed 125

- needle-beds and sets of independent needles and a cam-carrier for actuating the needles of both sets successively, the combination of rods on opposite sides of the longitudinal mid-plane, yarn-guides mounted movably on said rods, a yielding driver carried by the cam-carrier on each side of the longitudinal mid-plane to engage the corresponding yarn-guides, and means to disengage the yarn-guides automatically from the drivers and check their movement at different points in alternation on opposite sides of the longitudinal mid-plane. 10
13. In a knitting machine for knitting vertically striped fabric having two opposed needle-beds and sets of independent needles and a cam-carrier for actuating the needles of both sets successively, the combination of rods on opposite sides of the longitudinal mid-plane, yarn-guides mounted movably on said rods, a driver carried by the cam-carrier on each side of the longitudinal mid-plane to engage the corresponding yarn-guides, rods adjacent respectively to the first named rods, stops carried by said rods to disengage the yarn-guides from the drivers and check their movement at different points, and means to shift the last named rods and the stops thereon. 15
14. In a knitting machine for knitting vertically striped fabric having two opposed needle-beds and sets of independent needles and a cam-carrier for actuating the needles of both sets successively, the combination of rods on opposite sides of the longitudinal mid-plane, yarn-guides mounted movably on said rods, a driver carried by the cam-carrier on each side of the longitudinal mid-plane to engage the corresponding yarn-guides, rods adjacent respectively to the first named rods, stops carried by said rods to disengage the yarn-guides from the drivers and check their movement at different points, and means to shift the last named rods and the stops thereon, the last named rods being rotatable to prevent engagement of the stops with the yarn-guides. 20
15. In a knitting machine for knitting vertically striped fabric having two opposed needle-beds and sets of independent needles and a cam-carrier for actuating the needles of both sets successively, the combination of rods on opposite sides of the longitudinal mid-plane, yarn-guides mounted movably on said rods, a driver carried by the cam-carrier on each side of the longitudinal mid-plane to engage the corresponding yarn-guides, rods adjacent respectively to the first named rods, stops carried by said rods to disengage the yarn-guides from the drivers and check their movement at different points, and means to shift the last named rods and the stops thereon, the last named rods being rotatable to prevent engagement of the stops with the yarn-guides. 25

This specification signed this 20th day of June A. D. 1916.

ALVIN SCHWARTZ.
